UNITED STATES PATENT OFFICE

FRANK D. CHAPMAN, OF BERLIN, WISCONSIN

EXHAUST BOX OR COOKER

Application filed May 5, 1928. Serial No. 275,453.

This invention relates to improvements in exhaust boxes, more particularly adapted for use in the canning art.

In certain kinds of food put into cans, and particularly foods of an acid type, it is customary to run the cans through a steam or hot box in which the can is partly submerged in hot water, before the cover is placed on the can. The purpose of passing the can through the steam exhaust box is to both heat the food and drive out the air from the food, so that when the lid is sealed on the can, a vacuum will be created in the can. This is of great advantage from many points of view.

In a canning plant, which is arranged for canning various kinds of food as well as canning different sizes of cans of the same food, it is of considerable advantage, as the equipment for doing this work is already arranged, to subject the cans to various heating or cooking periods.

It is one of the objects of the present invention to provide an exhaust box or cooker which will accomplish the before mentioned features of advantage in a very simple manner.

A further object of the invention is to provide an exhaust box or cooker having a plurality of disks connected together in a manner to permit cooking food in open cans and variable as to time of cook.

A further object of the invention is to provide an exhaust box or cooker having disk means for giving the open cans of food a predetermined movement through the box or cooker from the inlet opening to the outlet opening or any portion of said movement.

A further object of the invention is to provide an exhaust box or cooker having disk means arranged to move open cans of food along one side portion of the box from one end to the other and then across said end to and returning along the other side portion of the box, and also having means for shunting the cans at intermediate points from one side of the box to the other.

A further object of the invention is to provide an exhaust box or cooker having a very simple means for controlling the adjustments

of the devices for shunting the cans from one side of the box to the other.

A further object of the invention is to provide an exhaust box or cooker which is of simple construction, is strong and durable and is well adapted for the purpose desired.

With the above and other objects in view, the invention consists of the improved exhaust box and cooker and its parts and combinations as set forth in the claims, and all equivalents thereof.

In the accompanying drawings in which the same reference characters indicate the same parts in all of the views:

Fig. 1 is a top view of the improved exhaust box or cooker, the cover being removed to show the parts therebeneath;

Fig. 2 is a longitudinal sectional view thereof, taken on line 2—2 of Fig. 1;

Fig. 3 is a vertical sectional view of one of the disk members and its bearing and a portion of the frame;

Fig. 4 is a side view on a larger scale, parts being in section, of one of the disk members and one of the shunting devices;

Fig. 5 is a top fragmentary view of one of the shunting devices.

Referring to the drawings, the reference numeral 8 indicates an exhaust box or tank of rectangular form, which is supported by angled legs 9 connected to the corners and medial portions of the tank. A removable cover 10 closes the upper open portion of the tank. A rectangular frame 11 within the box or tank is provided with transverse frame members 12 having depending bearings 13 connected thereto. Vertical shafts 14 adjustably journaled in said bearings 13 have geared disks 15 mounted on their upper ends. Said gears extend in two parallel lines adjacent opposite sides of the tank, the disks on the inner sides of the parallel lines being staggered with relation to the outer lines of disks and in mesh therewith, as clearly shown in Fig. 1.

At one end of the box a disk gear 15' is journaled which is in mesh with the two inner disk gears of the opposite sides of the box, so that all of the disk gears mentioned will be in mesh and form a continuous train of gears from one side of the box to the other.

A shunt disk gear 16 is journaled on one of the medial transverse frame members and is in mesh with the opposite side disk gears adjacent thereto, to provide a shunt can track between the disks of the opposite sides of the box. Similar shunt disk gears indicated by dotted lines 16' may be used if it is desired to provide other shunt can tracks.

The box 8 adjacent one side end is provided with an inlet opening 17 and on the opposite side end is provided with a discharge opening 18, and a feed disk gear 19 in mesh with an adjacent gear 15 is adapted to feed open cans of food through the inlet opening and into the box 8, while a discharge disk gear 20 in mesh with an adjacent gear 15 is adapted to discharge the cans 21 through the discharge opening 18 for further disposition.

A pinion 22, mounted on a shaft 23 in one corner of the box, is in mesh with the adjacent disk gear 15 and drives the before-mentioned chain of disk gears. The vertical shaft 23 on which the pinion 22 is mounted, is journaled in the same manner as the shafts 14. A bevel gear 24 mounted on the upper end of the shaft 23 is in mesh with a larger bevel gear 25 mounted on a horizontal shaft 26 which is provided on its outer end portion with a tight pulley 27 and a loose pulley 28. Said bevel gears and pulley 27 are the means for driving the machine, the power for the pulleys being derived by belt means (not shown) from a distant source of power.

Guide bars 29 extend above and along the advancing portions of the disk gears to form a zig-zag guideway over all of the disk gears from the inlet to the outlet opening of the box, as indicated by the arrows. These guide bars are spaced apart a sufficient distance to accommodate a single line of cans when in upright position, and the rotation of the advancing portions of the disk gears upon which the cans rest, will advance said cans along the guideway.

The shunting disk gear 16 is also provided with shunt guide bars 30 which are connected to and extend from the guide bars 29 on one side of the box to the similar guide bars 29 on the other side of the box. The guide bars 29 adjacent the shunt guide bars 30 are formed with gates 31 and 32 which may be swung from the solid line positions to the dotted line positions indicated in Fig. 1 to shunt the cans from one side of the box to the other before the cans reach the end of the box, and shorten the cooking period. When the gates 31 are swung to open position, the gates 32 will be swung to position to close the passageways 33 between the guide bars 29. A crank lever 60 and links 34 control the adjustment of the gates.

It is to be understood that the dotted line shunt disk gears may also be provided with shunt guide bars and gates if desired. The 65 guide bars are held in position by angled sup-

porting members 35 which are mounted on the transverse frame members and extend upwardly and are connected to the guide bars.

The height of the disk gears with relation to each other is adjusted by means of set 70 screws 36 which are threaded through caps 37 mounted on the lower ends of the bearings 13 and bear against the lower end of the shafts 14. Lock nuts 38 hold the set screws in adjusted position.

The portions of the guide bars 29 which project from the opposite sides of the box are formed with bottom portions to form chutes 39 and 40 for feeding cans to the box and discharging cans therefrom.

The bottom portion of the box is provided with an outlet opening 41 for discharging the water of condensation from the box, or in case hot water is used, the opening may be closed to retain the water during the cooking 80 operation.

Perforated steam pipes 42 extending around the inner sides of the box and central portions thereof, are positioned to spray jets of steam into the box and around the cans as the cans are rolled and advance between the guide in a zig-zag course from the inlet to the outlet opening. As the cans rest upon the advancing portions of the disk gears, the cans are moved forwardly in a zig-zag manner from one end of the guide to the other. In some kinds of food which does not require as much cooking as other kinds, the cans may be shunted across the medial portion of the box and will be subjected to approximately 90 one-half of the cooking period. Furthermore, disk gears and guide bars may be mounted in the manner indicated by dotted lines 16' to provide more cooking periods, as desired, thus providing a box with variable 95 cooking periods.

It is to be understood that the train of 100 geared disks may be arranged in various ways to provide variable cooking periods without departing from the spirit of the invention.

From the foregoing description, it will be seen that an exhaust box or cooker is provided which is very simple in construction, is efficient in operation and permits variable 110 cooking periods of cans of food while the cans are in open position.

What I claim as my invention is:

1. An exhaust box or cooker, comprising a receptacle having an inlet opening and an 120 outlet opening, means for heating the interior thereof, rotary means and a guide extending in two spaced lines for moving open cans of food through the receptacle in a circuitous path from the inlet to the outlet 125 opening of the receptacle to provide a certain time period for cooking the food within the open cans, and other rotary means between the two lines operable when desired for shunting the open cans from one portion of 130

the line of normal path of travel of the cans to another portion of the line of normal travel of the cans to shorten the cooking time period of the open cans of food.

- 5 2. An exhaust box or cooker, comprising a receptacle having an inlet opening and an outlet opening, means for heating the interior thereof, spaced lines of rotary disks for moving open cans of food through the receptacle from the inlet to the outlet opening, means for guiding the cans in a circuitous path from one disk to another in passing through the receptacle to provide a certain time period for cooking the food within the 10 open cans, and other rotary disks and guide means interposed in the space between the lines of disks for shunting the cans from the line of disks on one side of the space to the line of disks on the other side to shorten the 15 cooking time period of the open cans of food.
- 20 3. An exhaust box, comprising a closed receptacle having an inlet and an outlet opening, geared disks positioned within the receptacle and extending in two spaced zig-zag formation lines from the inlet to the outlet opening, curved guide means positioned above the disks and extending from one end to the other of the train of geared disks for guiding cans on said disks, another disk 25 interposed between the two lines of disks and geared thereto, another guide means positioned above the last mentioned disk and connected to the other guide means and having gates for deflecting cans from one 30 formation line to the other to shorten the cooking period of the cans of food, and perforated pipes within the receptacle and extending along portions of the path of travel of the cans for heating the food within the 35 cans.
- 40

In testimony whereof, I affix my signature.
FRANK D. CHAPMAN.
